UNITED STATES PATENT OFFICE.

LUCILLA DE VESCOVI, OF NEW YORK, N. Y., ASSIGNOR OF ONE-HALF TO BLANCHE P. SCRIBNER, OF NEW YORK, N. Y.

LADY'S UNDERGARMENT.

Application filed October 9, 1922. Serial No. 593,278.

To all whom it may concern:

Be it known that I, LUCILLA DE VESCOVI, a subject of the King of Italy, residing at New York, in the county of New York and 5 State of New York, have invented certain new and useful Improvements in Ladies' Undergarments, of which the following is a specification.

This invention relates to ladies' undergarments and more particularly to a brassière and to a novel combination of undergarments in connection therewith to form a single article of apparel.

One of the objects of the present invention is to provide a garment of the above character which is adapted to fit over and support the breasts, thereby to restrain the free movement thereof.

Another object is to provide a garment 20 of the above character having relatively few parts, which may be easily and inexpensively manufactured and assembled, and which may be laundered and freshened without harm to the garment.

Another object is to provide a garment of the above character that will take the place of several garments, that is, combine the brassière, vest or teddy or knickers in one piece.

A further object is to provide a brassière or garment of the last above character which will fit the form and give it sufficient support where needed, yet at the same time give all the desired freedom of movement and not detract in any way from the natural grace 35 of the wearer.

A further object is to provide a garment that will hold its place on the figure at all times regardless of movement of the arms.

A further object is to provide a brassière that will be exceedingly light and comfortable to wear at any time, one that will be free from unnecessary parts, straps and fastening means, and one that will completely enclose that portion of the body desired to be covered.

A further object is to provide a brassière that, because of its low-cut and inconspicuous character, is adapted to be conveniently worn with evening gowns.

Other objects will be in part obvious and in part hereinafter pointed out.

The invention accordingly consists in the features of construction, combination and arrangement of parts and in the unique re-

lation of the members and of the relative proportioning and disposition thereof, all as more completely hereinafter outlined. To enable others skilled in the art to fully comprehend and understand the underlying features of this invention and in order that they may embody the same by numerous modifications in structure and relation contemplated by this invention, drawings depicting a preferred form have been annexed 60 and made part of this disclosure, and in such drawings like letters of reference indicate corresponding parts throughout all the views, in which—

Figure 1 illustrates the parts constituting 70 the invention laid out flat;

Figure 2 is a perspective view showing the finished article from the rear constituting a combined brassière, vest and teddy or knickers according to the manner in which 75 the lower part is made; and

Figure 3 is a detail view showing the fastening means at the back.

Referring now to the drawings, and particularly Figure 1, the garment comprises 80 two portions, the upper or breast encircling portion 5 and the lower or waist embracing portion 6. In carrying out the general idea of simplicity and inexpensiveness of manufacture, these two portions are formed of one 85 piece which is divided by a tuck 7.

Describing the upper or breast encircling portion 5 in detail, this portion is slightly curved to form a front or neck portion 8 and is materially narrowed towards the back, the 90 extreme end portions being pleated as at 9 resulting in a further narrowing effect. Circular openings are provided in this portion to which are attached the pockets 10 which act as supports for the breasts. These 95 pockets may be formed by the four pieces 11, each piece being cut to form a substantially spherical triangle, and when stitched along their edges and to the edges of the openings hereinbefore mentioned form substantially hemispheres or segments of 100 spheres.

The lower portion 6 of the brassière proper forms a body enclosing band designed and intended to hold the garment in 105 place and prevents its riding up over the breasts when the arms are raised. The tuck and stitching 7, as shown by the dotted lines in Figure 1, has a strengthening and reinforcing effect and also provides a source of 110

attachment for the lower part of the garment such as the knickers or teddy 12, as shown in Figure 2. The form of such garment is immaterial, and forms no specific 5 part of the invention except in so far as it enters into a general application of the garment, that is, the combination of the brassière, vest and teddy.

At this point it might be well to note one 10 special advantage of this garment when combined with other undergarments as above described, namely, that it does away with the large number of straps over the wearer's shoulders. Heretofore, each of the 15 above noted garments has been supported by shoulder straps, and the different straps made an unsightly and uncomfortable arrangement, especially with evening dresses and similar garments. In order to present 20 a neat appearance with evening dresses or waists of transparent material it has been necessary heretofore to use some sort of a fastening device for holding all of the straps together, and this produced an awkward 25 bunching and was ineffective to prevent the continual separating or slipping of one or more of the straps. In the present garment only two straps 13 are used, one at each side, and they are preferably made of elastic material which not only holds the garment in 30 place, and permits freedom of movement, but by reason of their tensioned elasticity the straps are caused to cling securely to the shoulders without slipping.

35 Referring now to Figure 3, the back of the brassière has a peculiar overlapping elastic fastening which permits yielding in either or both lateral directions, yet at all times completely covers the back and does not 40 cause or allow any unsightly openings as do some other types of brassières now on the market. This is shown in detail in Figure 3, in which the breast encircling part 5, separated from the part 6 by the tuck 7, has 45 its adjacent ends 14 and 15 slightly overlapping and to the vertical edges of which are attached a plurality of elastic tabs 16 provided at their ends with the loops adapted to fasten over the buttons 17, for example. The lower part is preferably secured 50 by ordinary buttonholes and buttons 18. When the brassière is in place it will be seen that the breasts are held in anatomical position, being properly and naturally 55 spaced apart as in Figure 1, and a supporting action in four directions is obtained that is, up and down, by reason of the straps 13 and the body encircling band 6, and in both lateral directions by elastic tabs 16.

60 If desired the breast pockets 10 may be provided near the center with suitable fastening devices 20 whereby they may be partially opened when the garment is worn by nursing mothers.

65 While any desired material may be used

for the manufacture of this garment, it is preferred to use net for the upper part which is light, durable and form-sustaining, while the lower part in the better quality of garments should be of silk. 70

The brassière is also preferably low-cut and is inconspicuous when worn with evening gowns.

It is thus evident that the brassière provides an extremely light weight and yielding 75 garment and one that, although restraining the breasts from free movement due to the supports offered thereto in an up and down and side to side direction, does not subject the breasts to an uncomfortable pressure. 80

It is also obvious that the present invention provides a simple and practical garment which may be easily and inexpensively manufactured and well adapted to accomplish 85 among others all of the objects and advantages herein set forth.

Without further analysis the foregoing will so fully reveal the gist of this invention that others may readily adapt it for various 90 applications without omitting certain features that from the standpoint of the prior art fairly constitute essential characteristics of the generic or specific aspects of this invention, and, therefore, such adaptations should and are intended to be comprehended 95 within the meaning and range of equivalency of the following claims.

I claim:

1. An article of manufacture comprising 100 a one piece garment including a brassière having a body encircling part and a breast encircling part, said parts having a strengthening tuck therebetween, said body encircling part and said breast encircling part being open in the back and the adjacent 105 ends being held in overlapping position, elastic connectors at the ends of said breast encircling part to permit yielding in either or both directions, and elastic shoulder straps connected to the upper portion of said breast encircling part whereby the breasts are yieldingly supported in four directions. 110

2. An article of manufacture comprising 115 a brassière, a vest, and a lower member forming a single garment, said brassière comprising a breast encircling portion and a lower body encircling band, said breast encircling portion being provided with two spaced apart breast openings adapted to be closed by pockets, each pocket being formed of triangular parts joined together along their adjacent edges and to the edges of said openings, said lower body encircling band being separated from said breast encircling portion by a strengthening tuck and adapted 120 to prevent the brassière from riding up over the breasts when the arms are raised, said brassière adapted to open in the back and the adjacent ends thereof being held in overlapped position, elastic connectors on the 125 130

ends of said breast encircling portion to permit yielding of the overlapped edges thereof in either or both lateral directions and elastic shoulder straps joined to the top edge 5 of the brassière, said connectors and supporting straps adapted to effect a yielding support for the breasts in four directions, said vest, and lower member being secured to said body encircling band and being continued below said band as desired.

3. An article of manufacture comprising a brassière having a body encircling part and a breast encircling part, both of said parts being formed of a single piece of a net-like material and having a strengthening tuck therebetween, said breast encircling part being provided with two spaced apart breast openings adapted to be closed 15

by pockets, each pocket being formed of triangular parts joined together along their adjacent edges and to the edges of said opening, said brassière adapted to open in the back and having the adjacent ends thereof held in overlapping position, said breast encircling part having shortened ends where- 20 by the height of said ends is materially reduced, elastic fastening means on each overlapped end of said breast encircling portion to permit yielding thereof in either or both directions, and elastic shoulder straps connected to the top portion of said breast encircling portion whereby the breasts are 25 yieldingly supported in four directions.

In testimony whereof I affix my signature.

LUCILLA DE VESCOVI.
